CLAIM

The ornamental design for a baby crib, as shown and described.

DESCRIPTION

FIG. 1 is a front, right, and top perspective view of a baby crib showing our new design;

FIG. 2 is a front view of the baby crib of FIG. 1;

FIG. 3 is a rear view of the baby crib of FIG. 1;

FIG. 4 is a left view of the baby crib of FIG. 1;

FIG. 5 is a right view of the baby crib of FIG. 1;

FIG. 6 is a top view of the baby crib of FIG. 1;

FIG. 7 is a bottom view of the baby crib of FIG. 1; and,

FIG. 8 is another perspective view of the baby crib of FIG. 1, showing a configuration in which, awning brackets are mounted on the baby crib of FIG. 1. The broken (dashed) lines show portions of the baby crib that form no part of the claimed design. The broken lines in FIG. 8 showing the awning represent the environment only and form no part thereof.

1 Claim, 8 Drawing Sheets
